UNITED STATES PATENT OFFICE.

LEWIS W. KENNEY, OF LYNNFIELD, MASSACHUSETTS.

LAST.

Application filed April 30, 1927. Serial No. 187,910.

The invention to be hereinafter described relates to lasts which are formed of two sections, one of which is movable relatively to the other to shorten the last and thereby 5 facilitate removal of the shoe from the last and reapplication of the shoe thereto.

Heretofore, the fore and heel portions of sectional lasts have been connected by various devices, but so far as I am aware, these 10 have not been found to be satisfactory. Some of them require hollowing out and removal of so much stock from the last that it is objectionably weakened and frequent breakage results. Others have been connected by devices which, while permitting relative movement of the parts, the shoes 15 cannot be removed from the lasts without subjecting them to serious strains, particularly at the heel and front seams, and frequently they are torn.

The purpose of the present invention is to provide a last comprising fore and heel parts which are connected by means which is simple and cheap in construction, easily 25 applied and requires but little removal of stock from the last. Hence it is able to stand up under the hard usage which lasts necessarily experience. The means connecting the parts is contained wholly within 30 the last. The full outer contour of the last is retained and there are no interruptions or openings at the instep to interfere with proper and desirable shaping of the shoe.

The character of the invention will be 35 best understood by reference to the following description of one good form thereof shown in the accompanying drawing, wherein:

Fig. 1 is a side view of the last, the offset 40 position of the fore part with relation to the heel part being indicated in dotted lines;

Fig. 2 is a view of the top of the last;

Fig. 3 is a section taken on line 3—3 of Fig. 1; and

Fig. 4 is a section taken on the broken line 4—4 of Fig. 1.

Referring to the drawing, the last shown 50 therein as one good form of the invention, comprises a fore part 1 and a heel part 3 which meet on a plane 5 which has a sharp inclination rearwardly from the bottom to the top of the last.

The fore part has a kerf 7 therein, and 55 the heel part has a kerf 9 therein. These kerfs register and meet at the inclined plane 5. A guide and connecting plate 11 pro-

jects into the kerfs and is secured to the heel part by pins 13. This plate has an elongated slot 15 therein extending parallel to the inclined plane 5. A pair of pins 17 60 in the fore part project through the elongated slot and serve to connect the fore part with the plate, and at the same time permit limited sliding of the fore part along the inclined plane relatively to the rear part. 65

A socket 19 is in the fore part and extends to the plate and has lateral communication with the fore part kerf. This socket may conveniently be formed by boring through the bottom of the fore part, and the outer 70 end thereof may be closed by a suitable plug 21. In this socket is a coil spring 23 confined between the plate and a pin 24 at the bottom of the socket. Preferably this spring is under some tension when the fore and heel 75 parts are in normal relation.

The construction is such that the spring is compressible to permit the fore part to be slid from its full line position to its dotted line position shown in Fig. 1. When 80 moved to its full line position the pins 17 will slide along the slot and one of the pins will move out of engagement with an end of the slot. On release of the fore part the spring becomes effective automatically to restore the fore part to its normal position shown in full lines in Fig. 1. The fore part is slid by the spring until limited by engagement of one of the pins with the end 85 of the slot which serves as a stop. 90

To permit and prevent sliding of the fore part relatively to the heel part, a latch 25 is provided adjacent the juncture of the parts and is pivoted on a screw 27 at the top of the heel part. When the latch is 95 adjusted to the position shown in Figs. 1 and 2, it will overlie the top of the fore part and prevent shifting of the latter relatively to the heel part. When it is desired to slide the fore part relatively to the heel part, the latch is turned to a position in which it does not overlap the fore part. The heel part has the usual spindle socket 29 adapted to be mounted upon the jack spindle. 100

In preparing the last to receive the connecting means, it is merely necessary to make saw cuts in the fore and heel portions, bore the hole for receiving the spring, bore the holes for receiving the pins 13 and 17, insert the pins, introduce the spring into the bore, place the plug in the end of the bore, 110 and apply the latch to the heel part.

In use, the last is inverted and mounted on the jack spindle in the usual manner. When it is desired to remove the shoe from the last, the latch is released and then the 5 fore part is pressed downward against the opposition of the spring, thereby moving the fore part from its position shown in full lines to its position shown in dotted lines. This will substantially shorten the length 10 of the last, and the shoe will be slid rearward along the heel part of the last sufficiently to cause the heel seam to move away from the rear end of the last and allow ready 15 removal of the shoe therefrom without danger of tearing the heel or front seams, and without straining the shoe. On release of the pressure on the fore part, the spring will become effective automatically to restore 20 the fore part into normal relation with respect to the heel part. Then the latch is turned to its locking position.

By this invention a sectional last is provided which is strong and simple in construction, and cheap to manufacture. Shoes 25 may be quickly and easily taken off from the last and may be returned thereon for re-lasting without danger of injury to the shoes.

It will be understood that the invention is not limited to the specific embodiment 30 shown, and that various deviations may be made therefrom without departing from the spirit and scope of the appended claims.

What is claimed is:

A last comprising fore and heel parts 35 meeting on a plane inclined rearwardly from the bottom to the top of the last, said parts having registering kerfs therein meeting at said plane, a plate in said kerfs having an elongated slot therein, means to secure the plate to the heel part, pins in the fore part projecting through the elongated slot, the fore part having a socket therein, a coil spring in the socket confined between an end of the plate and the bottom of the 40 socket, said spring being compressible to permit sliding of the fore part along said plane into offset relation with the heel part, and on release of the fore part said spring being operable to slide the fore part along 45 the heel part, and a latch on the heel part adjustable to positions to permit and prevent sliding of the fore part relatively to the heel part.

LEWIS W. KENNEY.
